CENTRIFUGAL SWITCH

Fritz Heinzmann, Albershausen, Kreis Goep-pingen, Wurttemberg, Germany

Application February 28, 1951, Serial No. 219,449
In Germany March 17, 1950

1 Claim. (Cl. 200—80)

1

Induction motors are usually started by the aid of an auxiliary phase in which a current differing in phase from that of the working windings is produced. When the starting process is at an end and a certain speed has been attained, the auxiliary phase must be cut off automatically. This operation is carried out by means of a centrifugal switch. This switch comprises a centrifugal speed governor and two contacts which are broken and connected respectively by the governor.

Cutting off the auxiliary phase must take place instantaneously so that the spark may break off and the contacts be protected against erosion. Astatic or unstable adjustment is therefore required for the centrifugal governor. Furthermore, switching off the auxiliary phase must take place at a precisely fixed speed allowing only a small tolerance. If the speed is too low at the moment when the auxiliary phase is switched off, the motor will slow down and stop. If the speed is too high, the auxiliary windings will fuse. Small dimensions in length and diameter and absolute reliability in operation are further requirements such a switch has to meet. Furthermore, the rotating masses must be as small as possible; otherwise there will arise, after some time of service, a rattling noise which is not permissible with regard to the use most of the motors in question are designed for. Besides meeting the before-mentioned requirements the centrifugal switch must also be simple and inexpensive. Repulsion motors start with a high starting torque. After the motor has been started, the armature winding is short-circuited by a centrifugal switch, so that the motor continues working as an induction motor. In this case the centrifugal switch has to meet similar operating conditions. The switch must be reliable, operating instantaneously at a precisely fixed speed. If the starting time is too long, the motor will heat up too much and possibly get damaged.

The before-mentioned conditions are not or only partly met by the centrifugal switches used at present for the purpose in question. This deficiency will be removed by the present invention. According to this invention a centrifugal speed governor having radially arranged pressure springs—the design of such a governor in itself being known—is mechanically and functionally combined with a conducting ring fixed to the governor sleeve and sliding, while the motor is starting, on two stationary contacts. Besides this main feature there are other new features proving of value for the use in question.

2

Referring to the accompanying drawings: Fig. 1a is a perspective view. Fig. 1 is a longitudinal section, Fig. 2 a side view of such a centrifugal switch, while it is at rest, with closed contacts. Fig. 3 is a longitudinal section of the same centrifugal switch during normal work of the motor, the weights being swung out and the contacts separated from each other. Figs. 4, 5, and 6 show a side view, a longitudinal section, and a top view of one of the weights 1. Fig. 7 shows a contact mechanism as it has hitherto been most usual. Fig. 8 shows centrifugal force diagrams, the governor lift being drawn on the abscissa AB, and the centrifugal forces on the ordinate BC. X—X is the rotation axis of the centrifugal governor. Figs. 9 and 10 show side view and top view of the governor support.

The weights 1 are pivotally seated in the U-shaped part 2 by means of pivots 3. Part 2 is firmly connected with tube 4 fitted to the shaft. Parts 2 and 4 form together the governor support. The spring supports 5 supporting the inner ends of pressure springs 6 are movably seated in the weights 1. The outer ends of these springs are supported by nuts 7 screwed on to bolts 8 firmly fixed to tube 4. By means of arms 9 the weights 1 exert their pivoting action on governor sleeve 10. A conducting ring 11 is firmly fixed to sleeve 10. While the motor is starting, this ring slides on contacts 13 and 14 fixed to stationary contact bearer 12, thus conducting the current through these contacts. Conducting bars 15 are connected with the auxiliary phase.

Hitherto centrifugal governors having plate springs have sometimes been employed for the purpose in question. Such plate springs are exposed to breaking if they are not treated carefully enough. The spring force diagram varies according to but slight differences in thickness of plate, such differences being unavoidable in manufacturing plate springs. Tension springs, which are also used, are particularly exposed to breaking at their bent suspension loops. The spring force diagram shows rather considerable differences, no uniform initial tension being obtainable. Torsion springs acting on the link bolts, or axially arranged pressure springs are also used for the purpose in question. With such springs work consumed by friction is considerable, because the springs transmit their full load on the links. Hence it follows that the centrifugal switch operates at varying speeds owing to the varying conditions with regard to friction or lubrication. Plate springs or tension springs or torsion springs allow speed regulation only within a narrow range

and by using complicated means. Pressure springs, however, are easily adjustable, so that the characteristic and speed required for the purpose in question is obtainable with all desired accuracy. Furthermore, pressure springs are absolutely reliable in operation and resisting to fracture, however rude they may be treated. Speed control within a comparatively wide range is possible by simply adjusting the nuts 7. As the centrifugal force of the weights 4 directly opposes the force of the springs 6, friction is reduced to the minimum, so that the speed at which the switch is required to operate is always exactly the same.

Fig. 7 shows a contact device as it has hitherto been most usual. Plate spring 17 fixed to contact bearer 16 is stressed by the governor sleeve while contacts 18 and 19 are in closed position, whereas it is released when the weights move outwards, the contacts being disconnected at the same time. The lift of contact spring 17 is limited by plate 22. Fig. 8 shows the centrifugal force diagram $a-b-g-h$ of the centrifugal speed governor having transverse springs 6, the adjustment of the governor being astatic as it is necessary for obtaining an instantaneous operation. The centrifugal force diagram, which in this case is nearly in accordance with the diagram of the transverse springs, intersects the axis of the abscissa AB in the intersection point with the rotation axis. Sometimes unstable adjustment of the governor is advisable, so that the centrifugal force diagram intersects the axis of the abscissa in a point that is still more distant from a , being beyond the rotation axis X-X. Diagram $a-b-c-d$ represents the force diagram of the contact spring 17. This spring must have a certain minimum power to ensure safe disconnection of the contact 18. If the spring is too weak the contact does not break off, and the motor will be damaged. $a-c$ representing the contact spring force while the weights are in inward position, is longer than $b-d$ representing the contact spring force while the weights are in outward position, so that $a-b-c-d$ is the resultant centrifugal force diagram of the governor combined with contact spring 17. Hence it follows that the governor becomes static and thereby unserviceable for the purpose in question. If astatic or unstable adjustment of the governor combined with contact spring 17 shall be obtained, building-in uncommonly heavy weights is necessary in order to increase the difference between contact spring force diagram $a-b-c-d$ and centrifugal force diagram $a-b-g-h$. Such weights favour a noisy working of the governor and increase its construction dimensions.

The present invention removes the before-mentioned difficulty by providing the conducting ring 11 passing the current through contacts 13 and 14. In this case no additional spring power influencing the characteristic of the centrifugal governor in an unfavourable manner, is required. The diagram $a-b-c-d$ is non-existent.

The weights 4 are made of sheet metal by non-

cutting shaping, this working process being most simple. They are provided with a radial hole 21, an upright edge 22 having a rounded-off outside, and flaps 23 having a bent-in inside. The edge 22 and the flaps 23 serve to stiffen the weights, and help to increase the governing power. The outside of the edge 22 is rounded off in order to obtain an accordingly smaller outside diameter of the governor. The edge 22 engages in recesses 24 of the U-shaped part 2, which is also made of sheet metal by non-cutting shaping. By this arrangement the construction length is reduced. Fixed in part 2 is a tube 4 the bore of which depends on the diameter of the shaft.

15 The governor support and the weights may also be cast, die-cast, or pressed.

16 The conducting ring may also be carried on the governor sleeve in ball bearing seat, so that it does not move when being in contact with the contacts, whereby wearing down the contacts due to friction at the conducting ring will be avoided.

20 The new combination described in this specification and the additional features of this invention provide for the construction of a centrifugal switch that is reliable in service, easily adjustable, instantaneously switching, working with least possible noise, simplified and shortened in its design, whereby it meets the requirements such a device is desired for, in a manner that has hitherto been striven for by manifold vain efforts. As is apparent from the present specification, only part of these requirements would be achieved, if for example the centrifugal speed governor of the described construction were combined with a contact device of another construction, or the described contact device with another centrifugal speed governor.

25 I claim:

26 Centrifugal switch comprising a support fitted to the shaft, two weights pivotally connected with said support, pressure springs adapted to oppose the outward movement of said weights and having their outer ends in contact with nuts and their inner ends in contact with movably seated spring supports, said nuts being screwed on to stay bolt screws firmly fixed to said support, said spring supports being movably seated in said weights, a sleeve slidably seated on the shaft and movably connected with said weights, a conducting ring fixed to said sleeve, a contact bearer fixed to the stationary centrifugal switch casing, two contacts fixed to said contact bearer, conducting bars fixed to said contact bearer and connected with said contacts.

30 FRITZ HEINZMANN.
